United States Patent Office

Des. 210,421
Patented Mar. 5, 1968

210,421

PAIR OF SUNGLASSES OR THE LIKE

Atherton R. Mitchell, Dillon Beach, Calif., assignor to Renaud International, Ltd., Burlingame, Calif., a corporation of Delaware

Filed Jan. 31, 1967, Ser. No. 5,628

Term of patent 14 years

(Cl. D57—1)

glasses, showing my new design;

The temple is shown broken away in FIGURE 6 for convenience of illustration.

I claim:

The ornamental design for a pair of sunglasses or the like, substantially as shown and described.
